CLAIM

The ornamental design for a media storage tray, as shown and described.

DESCRIPTION

FIG. 1 is a pictorial view of a first embodiment of a media storage tray illustrating the top, left and front sides thereof; FIG. 2 is an elevational view of the front side of the media storage tray of FIG. 1;

FIG. 3 is an elevational view of the rear side of the media storage tray of FIG. 1;

FIG. 4 is an elevational view of the left side of the media storage tray of FIG. 1;

FIG. 5 is an elevational view of the right side of the media storage tray of FIG. 1;

FIG. 6 is a plan view of the top side of the media storage tray of FIG. 1;

FIG. 7 is a plan view of the bottom side of the media storage tray of FIG. 1;

FIG. 8 is a pictorial view of a second embodiment of a media storage tray illustrating the top, left and front sides thereof; FIG. 9 is an elevational view of the front side of the media storage tray of FIG. 8;

FIG. 10 is an elevational view of the rear side of the media storage tray of FIG. 8;

FIG. 11 is an elevational view of the left side of the media storage tray of FIG. 8;

FIG. 12 is an elevational view of the right side of the media storage tray of FIG. 8;

FIG. 13 is a plan view of the top side of the media storage tray of FIG. 8; and,

FIG. 14 is a plan view of the bottom side of the media storage tray of FIG. 8.

The broken lines shown in FIGS. 1 and 8 are for illustrative purposes only and form no part of the claimed design.
